E. J. WIRFS,
DOOR FASTENER,
APPLICATION FILED JUNE 29, 1918.

1,307,229.

Patented June 17, 1919.

UNITED STATES PATENT OFFICE.

EDWARD J. WIRFS, OF ST. LOUIS, MISSOURI.

DOOR-FASTENER.

1,307,229.

Specification of Letters Patent. Patented June 17, 1919.

Application filed June 29, 1918. Serial No. 242,628.

To all whom it may concern:

Be it known that I, EDWARD J. WIRFS, a citizen of the United States of America, a resident of the city of St. Louis, State of Missouri, have invented certain new and useful Improvements in Door - Fasteners, of which the following is a full, clear, and exact description, reference being had to the accompanying drawings, forming a part of this specification.

My invention relates to a fastener more particularly designed for use upon the doors of refrigerators or cold storage rooms, but applicable also to other doors which it is desired to so close as to form an air tight joint between the door and the jamb, or wall around an opening intended to be closed by the door.

Figure I is a side view of my door fastener shown applied to the door and wall of a refrigerator.

Fig. II is a front elevation, partly in vertical section.

Fig. III is a top view of the presser rod, the bracket in which said rod is operable and the rod operating means.

Fig. IV is an elevation, partly in horizontal section, of my door fastener and the portions of the door and refrigerator wall to which the fastener is applied.

In the drawings, A designates the wall of a refrigerator and B a door adapted to close a doorway in the wall A.

The wall A has secured to it a keeper 1 containing a socket 2 and having at its forward end an inclined face 3, which leads upwardly to the front end of said socket. Said inclined face is adapted to receive an anti-friction member carried by a latch arm 6 of my door fastener, which is adapted to enter into the socket 2, as will be herein-after fully described.

4 designates a spindle extending through the door B and preferably provided at its inner end with a handle 5 through the medium of which the spindle may be operated by a person situated within the refrigerator when the door B is closed. The spindle 4 has secured to it at its outer end a latch arm 6 adapted to engage the keeper 1 and preferably provided at its free end with a roller 7, or other anti - friction device, adapted to traverse the inclined surface 3 of the keeper and enter the socket 2.

All of the parts thus far described are 55 old and no invention *per se* is herein claimed for them.

8 designates a plate secured to the door B and having formed thereon, or secured thereto, a bracket 9 containing a vertical pocket 10. The pocket 10 is open at its lower end and is provided at its upper end with an aperture 11 surrounded by a spring seat shoulder 12.

13 designates a hand lever pivotally 65 mounted at 14 in a bifurcated extension 15 of the bracket 9 and provided with a rearwardly extending arm 16 terminating in a fork 17. Said arm 16 overlies the bracket 9, as seen in Figs. I and III.

18 designates a presser rod extending vertically through the bracket 9 at the location of the vertical pocket 10 therein. The upper end of said rod protrudes through the upper end of the bracket 9 and has arranged in it 75 a transverse pin 19, which is engaged by the fork 17 of the arm 16. The lower end of the presser rod is pivoted at 20 to the latch arm 6 and said presser rod is surrounded by a spring 21 seated between a shoulder 22 80 near the lower end of the rod and the spring seat shoulder 12 at the upper end of the pocket 10 in the bracket 9, said spring having a constant tendency to impart downward movement to the presser rod and thereby depress the latch arm 6.

In the use of my door fastener the latch arm 6 normally occupies a lowered position in which it is held by the spring 21, and if the fastener is in door holding position, as 90 seen in the drawings, the spring pressure acts upon the presser rod 18 to maintain the free end of the latch arm seated in the socket 2 of the keeper 1. When it is desired to open the door to which the fastener is applied, the operator grasps the hand lever 13 and by a forward pull thereon causes said lever to turn upon its pivot and the arm 16 to be elevated in an arc of a circle, thus causing said arm to exert a pull upon the presser 95 rod 18 and move it upwardly against the action of the spring 21. The presser rod in its upward movement lifts the latch arm 6 sufficiently to permit disengagement of the free end of the latch arm from the keeper 100 as the door is opened. It will be seen that when an operator exerts a forward pull upon the hand lever 13 to disengage the latch arm 105

from the keeper by which it was previously held, the direction of pull upon the hand lever is a direct one of such nature as will also serve to pull the door open, without any twisting or other complex movement of the operator's hand or arm, and therefore the operator is enabled to both unfasten and open the door by the simple act of pulling the hand lever 13 forwardly. In closing a door equipped with my fastener, it is only necessary to press the door closed and the anti-friction roller 7 will ride upwardly on the inclined face 3 of the keeper 1 and become seated in the socket 2 of said keeper, the spring 21 readily permitting upward movement of the latch arm 6 and the presser rod 18 at such time, and then forcing said parts downwardly to securely hold the anti-friction roller in the socket of the keeper.

Copies of this patent may be obtained for five cents each, by addressing the "Commissioner of Patents, Washington, D. C."

I claim:—

A door fastener comprising a keeper, a pivotal latch arm for engagement with said keeper, a bracket adjacent said latch arm provided with a spring pocket, a presser rod extending through said bracket and pivoted to said latch arm, a spring in said pocket surrounding said presser rod adapted to move said presser rod and latch arm in one direction, and a hand lever pivoted to said bracket having an arm pivoted to said presser rod whereby the presser rod and latch arm may be moved in a direction contrary to that in which they are moved by said spring.

In testimony that I claim the foregoing I hereunto affix my signature.

EDWARD J. WIRFS.
